CONTROLLER FOR ELECTRIC MOTORS

Richard B. Hunter, Shorewood, and Jesse E. Jones, Wauwatosa, Wis., assignors to Cutler-Hammer, Inc., Milwaukee, Wis., a corporation of Delaware

Application February 13, 1943, Serial No. 475,776

12 Claims. (Cl. 172—152)

This invention relates to controllers for electric motors, and more particularly to controllers affording so-called jam protection.

In Patent No. 1,579,018, March 30, 1926, two forms of drum type motor control, one of the plain reversing type and the other of the dynamic lowering type are disclosed with jam protection which has been found very advantageous in practice. In the first mentioned form of control the protective means is responsive, as for example when the motor stalls during operation in either direction, to re-include a predetermined amount of series resistance, whereas in the second mentioned form the protective means so functions but only when the motor is operating in hoisting direction.

In both cases when the protective means responds the same remains effective pending return of the control drum to off position.

The present invention has among its objects to improve both controllers disclosed in the aforementioned patent, the improvements including provision for low voltage protection during running and during jamming.

Another object is to simplify the means employed to afford jam protection and to obtain low voltage protection through the medium of instrumentalities used for jam protection.

Another object is to provide a drum controller with jam protecting means comprising electromagnetic contactors so utilized as to take arcing to which the drum contacts otherwise would be subjected.

Another object is to enable use of a jam relay having normally open contacts, such a relay being less susceptible to shocks and vibrations, and hence more suitable for use on shipboard.

Another object is to provide jam protective means functioning without interruption of motor torque.

Another object is to provide jam protective means applicable to different types of drum controllers, as for example a plain reversing drum or a dynamic lowering drum without change in the control circuits of said means and hence enabling for control of such circuits a standard arrangement of drum contacts.

Another object is to provide improved jam protective means applicable to controllers other than those aforementioned, whereas various other objects and advantages of the invention will hereinafter appear.

Certain embodiments of the invention are diagrammatically illustrated in the accompanying drawing which will now be described, it being

understood that the embodiments illustrated are susceptible of various modifications without departing from the scope of the appended claims.

In the drawing,

5 Figure 1 shows the invention applied to a plain reversing controller;

Fig. 2 shows a modification of the drum portion of the jam protective means, and

10 Fig. 3 shows the invention applied to a dynamic lowering controller.

Referring to Fig. 1, the same shows a drum type reversing controller essentially like that shown in the aforementioned patent but with the addition of means affording a shunt for the motor armature to be closed in the off position of the drum and in the first forward and reverse positions of the drum. More specifically Fig. 1 shows a motor M having an armature A and a series field winding F to be supplied with power from lines L₁ and L₂. The drum comprises contact fingers 1 to 5 and cooperating segments 1a, 2a, 3a, 4a and 2b, 3b, 4b, 5b for control of the direction of operation of the motor through reversals of the flow of current through the motor armature. Additionally the drum comprises contact fingers 6 and 7 and cooperating segments 6a and 7a, controlling an armature shunt for motor M including a resistor r. Additionally the drum includes contact fingers 8, 9, 10, 11, 12 and 13 and cooperating segments 8a to 13a and 8b to 13b which afford variation and exclusion of a series resistor R for the motor when the motor is caused to operate in either direction. The aforementioned reversing contacts provide for connection of the motor to line L₁, whereas the motor connections to line L₂ include a drum contact finger 14 and cooperating segments 14a and 14b.

35 The jam protective means includes an electromagnetic contactor N, an electromagnetic contactor J and an electro-responsive jam relay JR. The contactor N has normally disengaged contacts 15 which when engaged complete circuit from line L₂ to and through the winding 16 of the relay JR to drum contact finger 14. Thus line connection of the motor is dependent upon engagement of the drum finger 14 by one of its cooperating segments and also upon engagement of the contacts 15 of contactor N, whereas establishment of this connection subjects the winding 16 of relay JR to the motor current. The relay JR has normally disengaged contacts 17 which when engaged tend to complete an energizing circuit for the winding 18 of contactor J, this contactor having normally disengaged con-

tacts 19 which when engaged establish a circuit for jam protection. This circuit extends from a tap of series resistor R, which tap for illustration is shown as drum contact 12, to and through contacts 19 of contactor J to line L2, and when contactor J responds to establish this circuit it acts through its normally engaged contacts 20 to interrupt the circuit of the winding 21 of contactor N to cause the latter contactor through its contacts 15 to interrupt the first mentioned connection to line L2. As will be understood the portion of the resistor R thus reinserted for protection on jamming may be varied by adjustment of the tap of resistor R connected to the contacts of relay J.

Here it is to be noted that the jam relay JR is of the normally open type with the advantage aforementioned, and that both of the contactors J and N in respect of their main contacts 19 and 15 are of the normally open type. Moreover both contactors J and N are alike in having normally disengaged auxiliary contacts 22 and 23, respectively, and differ only in that contactor J has the aforementioned normally engaged contacts 20. Hence it will be apparent that the two contactors may be of like size.

Considering now the control means for the contactors J and N, it includes drum contact fingers 25, 26, 27 and 28, the contact finger 25 having a connection to line L1 and having a continuously engaging segment 25a. The segments 26, 27 and 28, on the other hand, have cooperating segments 26a, 28a and 27b, 28b. Contact fingers 26 and 27 are electrically connected, and segments 28a and 26a are connected to segment 25a while segments 28b and 27b are also connected to segment 25a. Thus when segment 28a is engaged with finger 28 circuit is completed from line L1 to segment 25a and segment 28a to contact finger 28 by conductor 29 through normally engaged contacts 20 of contactor J, to and through the winding 21 of contactor N to line L2, and the same connections are completed when contact finger 28 is engaged by segment 28b. One or the other of these segments engages contact finger 28 upon initial movement of the drum to start the motor in either direction, and thus provision is made for immediate energization of relay N to engage its contacts 15 whereby when the drum reaches its first operative position the motor line connections will be completed. When this occurs drum contact finger 26 will be engaged by segment 26a or drum contact finger 27 will be engaged by segment 27b and this establishes a connection from line L1 to drum contact 25, and thence to drum contact 27 or contacts 26 by conductors 30 and 31 to and through the now engaged contacts 23 of contactor N by conductors 32 and 29 to and through the winding 21 of contactor N as already traced. This circuit maintains the winding 21 energized when contact finger 28 is disengaged by its cooperating segment 28a or 28b. Also engagement of drum contact 26 or 27 by its respective finger provides a connection rendering closure of the contacts 17 of relay JR effective to connect the winding 18 of contactor J across lines L1, L2. More particularly circuit may be traced as already described from line L1 to conductor 30, thence through contacts 17 to and through winding 18 to line L1.

Thus with the motor operating in either direction response of the jam relay JR to an overload current in the motor circuit energizes winding 18 to cause response of contactor J with the result

of engaging its contacts 19 to complete the jam protective circuit aforesaid. At the same time contactor J through disengagement of its contacts 20 deenergizes contactor N and through engagement of its contacts 22 completes a shunt around contacts 17 of relay JR. Accordingly the contactor J upon responding establishes for itself a maintaining circuit which maintains said contactor energized pending return of the drum to disengage from finger 26 or 27, as the case may be, its cooperating segment. If meanwhile the relay JR has released to disengage its contacts 17 this will have no effect on contactor J, whereas when contactor J is released by the aforementioned return movement of the drum the motor is disconnected from line L2 and the starting cycle may be repeated.

Here it is to be noted that when jamming occurs contactor N remains energized until de-energized by opening of contacts 20 of contactor J, thus providing continuous motor torque during the transfer from running connections to jam connections. Also it is to be noted that if while contactor J or contactor N is energized there is a failure of voltage or an abnormal drop in voltage such contactors will release to entirely disconnect the motor from line L2 and to necessitate return of the drum to starting position in order to reconnect the motor to line L2. This will be apparent for the only energizing connections for the contactor N when the drum is in the running position will be interrupted by the then open contacts 23 of said contactor, whereas the connections for the winding 18 of contactor J will be opened both at the contacts 17 of relay JR and at the then open contacts 22 of relay J. Further it is to be noted that with the contactor J or the contactor N closed movement of the drum to off position provides for immediate de-energization thereof, causing it to take arcing to which otherwise the drum contacts would be subjected.

Fig. 2 shows a slight modification of the drum section constituting part of the jam protective means, the modification consisting in substituting for drum segments 28a and 28b of Fig. 1 a single segment 28c to engage contact finger 28 in the off position of the drum and to disengage it when the drum is moved to either its first forward position or its first reverse position. Thus as is obvious this modification provides for energization of contactor N in off position of the drum rather than upon initial starting operation of the drum as in Fig. 1. This modified control may be desirable under certain conditions.

Fig. 3 shows a dynamic lowering drum similar to that shown in the aforementioned patent, the motor M1 of Fig. 3 being shown as having an armature A, a series field F and a shunt field F1. This drum has for control of the motor circuits substantially the same contact arrangement as that of said patent, providing in off position a closed loop for the motor armature and field F, which loop includes a resistor r1, providing in its hoist positions a circuit through the motor armature and field F in series, and providing in its lowering positions a loop for the motor armature and field F with line connection of said loop such as to place the motor armature and field F in a parallel relation for reversal of the flow of current through the motor armature while maintaining the original polarity of the field F. The drum has resistance controlling contacts to afford suitable resistance control for both hoisting and lowering and like the drum of Fig. 1 it has

contacts between the motor and both sides of the supply line except as regards the shunt field F_1 which is permanently connected to line L_1 and connected to line L_2 through certain of the drum contacts.

In the control of Fig. 3 the jam protective means is the same as in Fig. 1, but in Fig. 3 the winding 16 of the jam relay JR is connected between the motor armature and the drum contacts which provide for connection to line L_1 for hoisting. Thus this relay winding is subjected to the motor current during hoisting, whereas it is not in circuit during lowering, this providing for protection against jamming in hoisting and insuring against undesired action of the protective means in lowering. Yet as aforesaid the jam protective means remains the same as in Fig. 1 even to the arrangement of the drum contacts forming part thereof.

As in Fig. 1 the contactor J of Fig. 3 controls circuit between a line L_2 and a tap of the motor controlling resistor and the action of the protective means in hoisting is the same as explained in connection with Fig. 1. In lowering contactor J never responds because relay JR is not in circuit and hence is unresponsive. Thus in lowering contactor N likewise is freed from influence by relay JR through contactor J , whereas in hoisting it is subject to control by relay JR through contactor J as explained in connection with Fig. 1. Accordingly it will be obvious that the protective means while modified in action to the extent indicated otherwise functions as in Fig. 1 with retention of its advantageous characteristics aforescribed including that of affording low voltage protection.

What we claim as new and desire to secure by Letters Patent is:

1. Control means for establishing operating connections and a jam protective connection for an electric motor, comprising a normally open electroresponsive switch requiring energization for normal motor operation, a normally open electroresponsive switch to be energized to establish a jam protective motor connection and to deenergize the former electroresponsive switch, and a normally open jam relay responsive to energize the second mentioned switch.

2. The combination with an electric motor, of control means to establish selectively different motor connections for normal operating conditions and for protection on jam, said means comprising for selection of such connections separate electroresponsive switches each of the normally open type and further comprising a jam relay of the normally open type responsive to motor current to effect selection of the second mentioned connections.

3. In an electric motor controller, the combination with control means to establish motor connections for normal operating conditions, said means comprising a manual control device and an electroresponsive switch of the normally open type under the control of said manual device, of a normally open jam relay and a normally open electroresponsive switch responsive under the control of said relay to establish protective motor connections and to maintain such protective connections independently of said relay but subject to control by said manual device.

4. In an electric motor controller, the combination with control means to establish motor connections for normal operating conditions, said means comprising a manual control device and an electroresponsive switch of the normally open

type under the control of said manual device, of a normally open jam relay and a normally open electroresponsive switch responsive under the control of said relay to establish protective motor connections and to maintain such protective connections independently of said relay, but subject to control by said manual device, the first recited electroresponsive switch being subject to deenergization by response of the last recited electroresponsive switch.

5. In an electric motor controller, the combination with control means to establish motor connections for normal operating conditions, said means comprising a manual control device and an electroresponsive switch of the normally open type under the control of said manual device, of a normally open jam relay and a normally open electroresponsive switch responsive under the control of said relay to establish protective motor connections and to maintain such protective connections independently of said relay but subject to control by said manual device, the first recited electroresponsive switch being subject to deenergization by response of the last recited electroresponsive switch, and the first recited switch when deenergized requiring for reenergization thereof manipulation of said manual device.

6. The combination with a drum controller for electric motors, of an electroresponsive switch controlled by said drum controller and coacting therewith to establish motor connections for normal motor operations, a jam relay and an electroresponsive switch under the control of said relay and said drum controller jointly to coact with said drum controller to establish protective motor connections, the last recited switch upon so functioning causing opening of the first recited switch, said drum controller having an arrangement of contact fingers and segments for control of said electroresponsive switches such that no change in drum control of said electroresponsive switches is needed whether the drum controller is of the plain reversing type with the jam relay effective for reverse motor operations or is of the dynamic lowering type with the jam relay effective only in hoist direction.

7. The combination with a drum controller for electric motors, of an electroresponsive switch controlled by said drum controller and coacting therewith to establish motor connections for normal motor operations, a jam relay and an electroresponsive switch under the control of said relay and said drum controller jointly to coact with said drum controller to establish protective motor connections, the last recited switch upon so functioning causing opening of the first recited switch, said electroresponsive switches being of the normally open type, and said drum controller having an arrangement of contact fingers and segments for control of said electroresponsive switches such that no change in drum control of said electroresponsive switches is needed whether the drum controller is of the plain reversing type with the jam relay effective for reverse motor operations or is of the dynamic lowering type with the jam relay effective only in hoist direction.

8. The combination with a drum controller for electric motors, of an electroresponsive switch of the normally open type controlled by said drum controller and coacting therewith to establish motor connections for normal motor operations, of a jam relay and an electroresponsive switch of the normally open type under the control of

said relay and said drum controller jointly to coact with said drum controller to establish protective motor connections, the last recited switch upon responding causing opening of the first recited switch and establishing for itself a maintaining circuit independent of said relay but subject to control by said drum controller, said drum controller having an arrangement of contact fingers and segments for control of said electroresponsive switches such that no change in drum control of said electroresponsive switches is needed whether the drum controller is of the plain reversing type with the jam relay effective for reverse motor operations or is of the dynamic lowering type with the jam relay effective only in the hoist direction.

9. The combination with a drum controller for electric motors, of an electroresponsive switch of the normally open type controlled by said drum controller and coacting therewith to establish motor connections for normal motor operations, a jam relay of the normally open type, and an electroresponsive switch of the normally open type under the control of said relay and said drum controller jointly to coact with said drum controller to establish protective motor connections, the last recited switch upon so functioning causing deenergization of the first recited switch and establishing for itself a maintaining circuit independent of said jam relay but controllable by said drum controller, and said drum controller having an arrangement of contact fingers and segments for control of said electroresponsive switches such that no change in drum control of said electroresponsive switches is needed whether the drum controller is of the plain reversing type with the jam relay effective only in the hoist direction.

10. The combination with a drum controller for electric motors, of an electroresponsive switch of the normally open type controlled by said drum controller and coacting therewith to establish motor connections for normal motor operations, a jam relay of the normally open type and an electroresponsive switch of the normally open type under the control of said relay and said drum controller jointly to coact with said drum controller to establish protective motor connections, the last recited switch upon so functioning causing deenergization of the first recited switch and establishing for itself a maintaining circuit independent of said jam relay but controllable by said drum controller, and said drum

controller having an arrangement of contact fingers and segments for control of said electroresponsive switches such that no change in drum control of said electroresponsive switches is

5 needed whether the drum controller is of the plain reversing type with the jam relay effective for reverse motor operations or is of the dynamic lowering type with the jam relay effective only in the hoist direction, the aforementioned arrangement of contact fingers and segments being such that the first recited switch when deenergized requires for reenergization thereof positioning of said drum controller to afford motor starting protection.

10 15. 11. In an electric motor controller, in combination, a normally open electroresponsive switch requiring energization for normal motor operation, a normally open electroresponsive switch to be energized to establish a jam protective connection

20 and to deenergize the former switch, said switches under predetermined low voltage conditions insuring disconnection of the motor, and control means for said switches including a jam relay responsive to energize the second mentioned

25 switch and requiring energization for energization of the second mentioned switch after release of the latter resulting from low voltage, and further including for control of the first mentioned switch means which may be set to prevent automatic response of the first mentioned switch upon restoration of normal voltage following release of the first mentioned switch through drop in voltage.

30 12. In an electric motor controller, in combination, control means to establish motor connections for normal operation, said means comprising an electroresponsive switch in the motor connections to open under predetermined low voltage

35 conditions, and further comprising a control device for said switch having starting and running positions and requiring return to starting position for energization of said switch after its release as a result of low voltage, and jam protective means including an electroresponsive switch

40 45 responsive only under jam conditions to establish an alternate motor connection and to deenergize the first mentioned switch, the second mentioned switch releasing under predetermined low voltage conditions to interrupt said alternate motor connection.
